STORAGE RECEPTACLE FOR TOILET PAPER

Theodore R. Black, Tipp City, Ohio

Application April 18, 1945, Serial No. 589,075

7 Claims. (Cl. 312—113)

1

This invention relates to a storage receptacle or magazine for toilet paper or the like.

One object of the invention is to provide such a receptacle which can be built into the wall of a bathroom or toilet room and rigidly supported therein in such a manner that portions only thereof are exposed and do not detract from the appearance of the room.

A further object of the invention is to provide such a receptacle having means whereby a roll of paper may be supported exteriorly of the lower end thereof and in which the rolls stored in the receptacle are supported out of contact with the exterior roll.

A further object of the invention is to provide such a receptacle having hinged closures for both the upper and lower ends thereof and in which the lower closure is arranged to permit a portion of the exterior roll to extend into the receptacle.

A further object of the invention is to provide such a receptacle in which the lower closure is movable forwardly through the lower end of the receptacle and is provided with a resilient latch to retain the same in its closed position.

A further object of the invention is to provide such a receptacle having means for releasably supporting the lowermost roll in the receptacle at a point spaced from the lower end of the receptacle.

A further object of the invention is to provide such a receptacle which is of a simple inexpensive construction, easy to install in the wall and of such a character that the rolls of paper may be easily inserted in and removed from the same.

Other objects of the invention may appear as the device is described in detail.

In the accompanying drawing Fig. 1 is a front elevation of a storage receptacle embodying the invention, showing the same installed in the wall; Fig. 2 is a vertical section taken centrally through the structure of Fig. 1; Fig. 3 is a sectional detail, partly broken away, of the closure for the upper end of the receptacle; and Fig. 4 is a sectional detail showing the resilient latch for the lower closure.

In the drawing I have illustrated the preferred embodiment of my invention and have shown the same as comprising a tubular structure 5 substantially rectangular in cross section and comprising front, rear and side walls rigidly connected one with the other. The upper and lower ends of the tubular structure extend forwardly, and the upper and lower ends 6 and 7 of the rear wall are curved forwardly, the front wall

2

having its upper and lower edge portions 8 and 9 bent forwardly and substantially parallel with the forward edge portions of the curved ends 6 and 7 of the rear wall. The cross sectional dimensions of the device are such as to permit a roll of toilet paper to be supported therein in horizontal position and to move freely in the receptacle and the overall length of the receptacle is such as to accommodate the desired number of rolls to be stored.

That wall of the toilet or bathroom which is in the rear of the water closet usually comprises six inch studding so that the space within the wall between the studding is ample to receive a receptacle of a fore and aft width slightly greater than the diameter of the roll of toilet paper. The receptacle is mounted in the wall before the construction of the latter has been completed. In the arrangement here shown the covering for

15 the wall comprises an inner supporting structure 10, such as wall board or lath, to which is applied an outer covering 11 of plaster. A convenient way of installing the device is to omit a section of the wall covering, of a size sufficient to permit the receptacle to be inserted between adjacent studding.

20 When so inserted the front lower portion of the rear wall rests upon the wall board and plaster at the lower end of the opening and the front edge of the upper portion of the rear wall is in contact with or close to the wall board and plaster at the upper end of the opening. With the receptacle in this position the wall board and plaster are applied to the studding between the forwardly projecting portions 8 and

25 9 of the front wall of the receptacle, the plaster extending slightly beyond the front edges of these portions, thus completing the wall and providing a continuous wall surface, except only for the open ends of the receptacle. A flanged

30 rim structure 12 is then inserted in the open upper end of the receptacle between the forwardly projecting edge portions 6 and 8 of the rear and front walls, with its flange 13 in contact with the plaster surrounding the opening.

35 40 The edge portions of the receptacle and the rim are then rigidly secured to the wall board and plaster, as by nails 14. A similar flanged rim 15 is inserted in the lower opening of the receptacle between the opposed edge portions 9 and 7 of the front and rear walls and is similarly secured in place.

45 Means are provided for supporting a roll of paper exteriorly of the receptacle at the lower end thereof and, in the present arrangement, this means comprises brackets 16 secured to the

vertical portions of the flange 15a of the rim 15 and provided with aligned openings to removably support a shaft 17 on which an exterior roll of paper 18 is supported. The brackets are, of course, spaced apart a distance greater than the axial length of the roll so that when the shaft 17 is removed a roll may move from the interior of the receptacle through the open end thereof. The shaft is spaced from the front end of the receptacle a distance less than the radius of the complete roll of paper so that a substantial portion of the roll will extend into the receptacle. It is desirable that the lower opening of the receptacle shall be provided with a suitable closure and in the arrangement here shown a door 19 is 15 hinged at its lower edge, at 20, to the rim 15 and is of such width that it may move forwardly about the hinge between the brackets 16 to a fully open position, as shown in dotted lines in Fig. 2. This door is preferably curved rearwardly so as not to restrict the extent to which the exterior roll of paper may extend into the receptacle and it is provided at its upper edge with latching means for retaining it in its closed position. The door is preferably of resilient material and is provided at its upper end with a recess 21 adapted to receive a lug 22 rigidly secured to the rim 15. A finger piece 23 extends downwardly from the groove portion of the door. When a forward and downward force is exerted on the finger piece 23 the door will flex and the rear wall of the groove will move beneath the lug 22, thus releasing the door for forward movement. When the door is moved rearwardly to its closed position the rounded rear wall of the groove will engage the lug and will spring downwardly to permit the lug to enter the groove and thus secure the door against movement.

Means are also provided for supporting the lowermost roll within the receptacle at a point 40 above the lower end thereof so that the lower roll will not engage the door and tend to force the same open. For this purpose I have mounted on the outer surface of one side wall of the receptacle a resilient latch 24 having a roll engaging portion 25 which extends inwardly through a slot 26 in the side wall and is provided in its inner end with a finger piece 27. The resiliency of the latch retains the roll supporting portion 25 normally in the path of the lowermost roll and thus supports all the rolls against downward movement. When it is desired to remove the lower roll the shaft 17 is removed, the door 19 opened and the latch 24 moved outwardly to release the lower roll, the latch being permitted to swing out into the path of the next following roll as the lower roll moves past the same.

The upper end of the receptacle is also provided with a closure 28 which is here shown as a flanged door, the upper flange of which is hinged at 29, to the flange 13 of the rim 12. The door is provided with a handle 30 by means of which it may be readily opened to permit the insertion of the rolls of paper and, if desired, a latch may be provided for retaining the same in its closed position but ordinarily the weight of the door will be sufficient to maintain it in its closed position.

While I have shown and described one embodiment of my invention I wish it to be understood that I do not desire to be limited to the details thereof as various modifications may occur to a person skilled in the art.

Having now fully described my invention, what

I claim as new and desire to secure by Letters Patent, is:

1. A storage receptacle for rolls of paper comprising a rigid vertical tubular structure substantially rectangular in cross section and adapted to be mounted in a wall between adjacent studding, the upper and lower end portions of the front and rear walls of said structure extending forwardly to engage said wall and support said tubular structure therein, means for removably supporting a roll of paper in line with and extending partially into the lower end of said structure, a closure hinged to said structure within the lower end portion thereof for forward movement to an open position, and yieldable means for retaining said closure in its closed position.

2. A storage receptacle for rolls of paper comprising a rigid vertical tubular structure substantially rectangular in cross section and adapted to be mounted in a wall between adjacent studding, the upper and lower end portions of the front and rear walls of said structure extending forwardly to engage said wall and support said tubular structure therein, means for removably supporting a roll of paper in line with and extending partially into the lower end of said structure, a door of resilient material in the forwardly extending lower end portion of said tubular structure, and hinged at its lower edge to said structure for forward movement to an open position, a lug secured to said structure adjacent the upper edge of said door, said door being curved rearwardly about a horizontal axis and having in its upper edge a recess to receive said lug, the rear wall of said recess being shaped to yield and ride over said lug when said door is moved to or from its closed position.

3. A storage receptacle for rolls of paper comprising a rigid vertical tubular structure substantially rectangular in cross section and adapted to be mounted in a wall between adjacent studding, the upper and lower end portions of the front and rear walls of said structure extending forwardly to engage said wall and support said tubular structure therein, means for removably supporting a roll of paper in line with and extending partially into the lower end of said structure, a closure hinged to said structure within the lower end portion thereof for forward movement to an open position, yieldable means for retaining said closure in its closed position, and a yieldable roll supporting device mounted on said tubular structure above the lower end thereof and held normally in the path of the lowermost roll in said tubular structure.

4. A storage receptacle for rolls of paper comprising a rigid vertical tubular structure substantially rectangular in cross section and adapted to be mounted in a wall between adjacent studding, the upper and lower end portions of the front and rear walls of said structure extending forwardly to engage said wall and support said tubular structure therein, rims extending respectively into the forwardly extending upper and lower ends of said tubular structure and having flanges to engage the outer surface of said wall, means for securing said rims to the respective ends of said structure and to said wall, and closures for the upper and lower ends of said structure hinged to the respective rims.

5. A storage receptacle for rolls of paper comprising a tubular structure substantially rectangular in cross section and having a vertical portion and a lower forwardly extending portion, a

5

door in said forwardly extending portion hinged at its lower edge to said structure for forward movement to an open position and curved rearwardly about a horizontal axis, and a lug secured to the upper wall of said forwardly extending portion, said door having at its upper edge upwardly extending front and rear projections adapted to receive said lug between them and said door being resilient to enable the rear projection to ride over said lug.

6. A storage receptacle for rolls of paper comprising a tubular structure substantially rectangular in cross section and having a vertical portion and a lower forwardly extending portion, a door in said forwardly extending portion hinged at its lower edge to said structure for forward movement to an open position and curved rearwardly about a horizontal axis, a lug secured to the upper wall of said forwardly extending portion, said door having at its upper edge upwardly 20 extending front and rear projections adapted to

6

receive said lug between them and said door being resilient to enable the rear projection to ride over said lug, and a roll supporting device mounted on the vertical portion of said structure for movement into and out of supporting engagement with the lowermost roll in said structure and to thereby support said lowermost roll in spaced relation to said door.

7. A storage receptacle for rolls of paper comprising a tubular structure substantially rectangular in cross section and having a vertical portion and a lower forwardly extending portion, means for supporting a roll of paper exteriorly of said structure with its rear portion extending into the forwardly extending portion of said structure, a yieldable device mounted on the exterior surface of said vertical portion and having a part extending into said structure in the path of the lowermost roll in said structure.
